FOUNTAIN PEN

Filed Feb. 20, 1931

UNITED STATES PATENT OFFICE

WILLIAM J. WOOLDRIDGE, OF MANSFIELD, OHIO

FOUNTAIN PEN

Application filed February 20, 1931. Serial No. 517,279.

This invention relates to a fountain pen and one object of the invention is to provide a pen the barrel of which is adapted to receive a sealed ink cartridge or capsule and the pen stock of which has means for opening said cartridge when the barrel is attached to the pen stock, thus permitting ink to flow to the pen point.

A further object of the invention is to provide a cartridge having a removable closure and a pen stock having means for engaging that closure and moving the same out of the opening in the cartridge when the barrel of the pen is attached to the pen stock.

15 A further object of the invention is to provide such a pen in which the closure for the cartridge will be supported by the pen stock after it has been removed from the opening in the cartridge and will be reinserted in that cartridge when the pen stock is detached from the barrel.

20 A further object of the invention is to provide an ink cartridge which will be simple in its construction and which may be easily filled 25 and sealed.

Other objects of the invention will appear as the device is described in detail.

In the accompanying drawings Fig. 1 is a longitudinal sectional view of a pen embodying my invention; partly broken away, and with a part of the pen stock in elevation; Fig. 2 is a similar view showing the barrel detached from the pen stock and the sealed cartridge partly inserted in the barrel; Fig. 3 35 is a rear end view of the pen stock; and Fig. 4 is a plan view of the sealed end of the cartridge.

40 In these drawings I have illustrated one embodiment of my invention but it will be understood that this has been chosen for the purpose of illustration only and that the device may take various forms without departing from the spirit of the invention.

45 As here shown, the pen comprises a pen supporting and feeding portion 5 which may be conveniently termed the pen stock, and detachably connected with the pen stock is a tubular member or barrel 6. In the present instance, the inner end of the pen stock is 50 provided with internal threads and the inner

end of the barrel is provided with external threads, as shown at 7, whereby the two parts may be connected with and disconnected from one another. In order that the pen may be quickly and easily filled without liability of getting ink on the fingers I have provided a cartridge adapted to be filled with ink and sealed and then inserted in the barrel of the pen, the sealing closure for the cartridge being of such a character that it may 55 be engaged and removed by a part connected with the pen stock when the barrel is screwed onto the pen stock. As here shown, the cartridge comprises a tubular member 8 closed at one end and adapted to fit within the barrel 6 of the pen. At its upper end the cartridge is provided with a relatively large opening 9 through which it may be filled and through which the ink may escape to the pen stock when the cartridge is assembled in the 60 pen. The opening 9 is preferably of uniform diameter throughout its length and is screw threaded. After the cartridge has been filled a screw threaded closure 10 is inserted in the opening 9 and is preferably screwed down 65 until its outer surface is flush with the end of the cartridge. When the cartridge is to be placed in the pen the barrel is detached from the pen stock, the cartridge inserted in the barrel and the barrel then again attached to the pen stock. The pen stock is provided with a stud 11 adapted to engage the closure 9 and screw the same through the opening and beyond the inner end of the opening, so as 70 to completely remove the same from the opening. Preferably the closure is provided in its outer side with a screw threaded socket 12 and the stud 11 has its end portion screw threaded to enter the socket 12. The socket 75 is arranged centrally of the cartridge and the stud 11 is arranged axially of the pen stock. When the cartridge has been inserted in the barrel and the barrel is screwed onto the pen stock the stud 11 will be screwed into the socket 12 and when it reaches the lower 80 end of the socket will cause the closure to rotate therewith in a direction to screw the same out of the opening 9 and to support the same in spaced relation to the end wall of the cartridge. In the form illustrated the 85

90

95

100

threads in the opening 9 and on the closure 10 are so arranged that the closure will be moved inwardly and supported beyond the inner end of the opening, as shown in Fig. 1.

5 The stud 11 may be connected with the pen stock in any suitable manner but, in the present instance, the pen stock is provided with a transverse partition 13 which carries the stud 11 and which is provided with openings 14 to permit the ink to flow from the cartridge to the pen point. Any suitable means may be provided for holding the cartridge against rotation within the barrel of the pen, and, as here shown, the lower end of the cartridge is provided with a rib 15 adapted to enter a groove 16 in the closed end of the barrel. When the barrel is removed from the pen stock the closure 10 will be again screwed into the opening 9 and, if no obstruction is offered to its movement, may be screwed entirely through that opening and remain on the stud 11. This, however, would necessitate the removal of the closure from the stud with the likelihood of getting ink on the fingers. I therefore prefer to provide means which will cause the stud to be unscrewed from the closure, leaving the latter in the opening in the cartridge. Inasmuch as the closure must be screwed into the opening 30 from the outer side thereof when the filled cartridge is sealed I have provided a stop which may be secured to the end of the cartridge after the closure has been placed in position and which will overlie the closure to prevent the same from being moved outwardly beyond the end wall of the cartridge. As here shown, this stop is L-shaped in form, as shown at 17, and one arm thereof is inserted in a socket in the end of the cartridge adjacent to the opening 9 and is preferably cemented therein, the other arm of the stop extends laterally beyond the end of the opening so as to overlie the closure. Thus when the barrel is detached from the pen stock the closure will be screwed into the opening until it contacts with the stop and the stud will then be screwed out of the closure, thus leaving the closure in the cartridge. If the cartridge is empty it may be removed and thrown away and a new cartridge inserted without danger of getting ink on the fingers. If the cartridge contains ink which it is desired to preserve it is properly sealed when the barrel is separated from the pen stock so that the ink will not be spilled. This arrangement also permits of interchangeably using inks of different color with one pen, as one cartridge can be readily sealed and removed and another cartridge substituted therefor.

60 While I have shown and described one embodiment of my invention I wish it to be understood that I do not desire to be limited to the details thereof as various modifications may occur to a person skilled in the art.

65 Having now fully described my invention,

what I claim as new and desire to secure by Letters Patent, is:

1. In a fountain pen comprising a pen stock and a barrel detachably connected therewith, an ink cartridge removably supported in said barrel and having an opening in that end adjacent to said pen stock, a closure for said opening adapted to be inserted therein from the outer side thereof, and means carried by said pen stock to engage said closure and move the same from said opening and beyond one end thereof when said pen stock is attached to said barrel. 70
2. In a fountain pen comprising a pen stock and a barrel having screw threaded connection with said pen stock, an ink cartridge removably supported in said barrel and having an opening in the end thereof, a closure removably mounted in said opening, and means carried by said pen stock to engage said closure, remove the same from said opening and support said closure in spaced relation to the opening when said pen stock is screwed onto said barrel. 80
3. In a fountain pen comprising a pen stock and a barrel having screw threaded connection with said pen stock, an ink cartridge removably supported in said barrel and having an opening in the end thereof, and a closure screwed into said opening, said pen stock having a part to engage said closure while said pen stock is being screwed onto said barrel and to screw said closure out of said opening. 90
4. In a fountain pen comprising a pen stock and a barrel having screw threaded connection with said pen stock, an ink cartridge removably supported in said barrel and having an opening in the end thereof, a closure screw threaded into said opening, and a part carried by said pen stock and adapted to be connected with said closure when said pen stock is screwed onto said barrel and to screw said closure out of said opening and support the same within said cartridge in spaced relation to said opening. 100
5. In a fountain pen comprising a pen stock and a barrel having screw threaded connection with said pen stock, an ink cartridge removably supported in said barrel and having an opening in the end thereof, a closure screwed into said opening and having a socket in the outer side thereof, and a stud carried by said pen stock and adapted to enter said socket and rotate said closure in a direction to move the same beyond one end of said opening when said pen stock is screwed onto said barrel. 115
6. In a fountain pen comprising a pen stock and a barrel having screw threaded connection with said pen stock, an ink cartridge removably supported in said barrel and having an opening in the end thereof, a closure screwed into said opening and having a screw threaded socket in the outer side thereof, and 125

5 a stud carried by said pen stock and having its end threaded to enter said socket when said pen stock is screwed onto said barrel, said socket having means to limit the movement of said stud therein and cause said closure to rotate with said stud, whereby said closure will be moved beyond the inner end of said opening.

7. In a fountain pen comprising a pen stock and a barrel having screw threaded connection with said pen stock, an ink cartridge removably supported in said barrel and having an opening in the end thereof, a closure screwed into said opening and having a shallow threaded socket in the outer side thereof, and a stud carried by said pen stock, adapted to be projected through said opening and having its end threaded and arranged to enter said socket when said pen stock is screwed onto said barrel.

8. In a fountain pen comprising a pen stock and a barrel having screw threaded connection with said pen stock, an ink cartridge removably supported in said barrel and having an opening in the end thereof, a closure screwed into said opening and having a screw threaded socket in the outer side thereof, and a stud carried by said pen stock and having its end threaded to enter said socket when said pen stock is screwed onto said barrel, said socket having means to limit the movement of said stud therein and cause said closure to rotate with said stud, whereby said closure will be moved beyond the inner end of said opening when said barrel is screwed onto said pen stock and will be inserted in said opening from the inner end thereof when said barrel is screwed off of said pen stock, and means to prevent said closure from being moved beyond the outer end of said opening when said barrel is removed from said pen stock.

9. In a fountain pen comprising a barrel and a pen stock adapted to be connected one with the other by relative rotary movement, an ink cartridge removably supported in said barrel and having a screw threaded opening in one end, a screw threaded closure inserted in said opening, and means actuated by the relative rotation of said barrel and said pen stock to screw said closure out of said opening.

10. In a fountain pen comprising a barrel and a pen stock adapted to be connected one with the other by relative rotary movement, an ink cartridge removably supported in said barrel and having a screw threaded opening in one end, a screw threaded closure inserted in said opening from the outer side thereof and adapted to move through said opening and beyond the inner end thereof, and means actuated by the relative rotation of said barrel and said pen stock to move said closure through said opening.

11. In a fountain pen comprising a pen

stock and a barrel having screw threaded connection with said pen stock, an ink cartridge removably supported in said barrel and having an opening in the end thereof, a closure screwed into said opening and having a screw threaded socket in the outer side thereof, a stud carried by said pen stock and having its end threaded to enter said socket when said pen stock is screwed onto said barrel, said socket having means to limit the movement of said stud therein and cause said closure to rotate with said stud, whereby said closure will be moved beyond the inner end of said opening when said barrel is screwed onto said pen stock, said barrel and said cartridge having parts cooperating to prevent the rotation of said cartridge with relation to said barrel.

12. An ink cartridge for a fountain pen comprising a tubular member closed at one end and having an opening through its other end, said opening being of uniform diameter and threaded throughout its length, and a threaded closure of uniform diameter throughout its length adapted to be screwed into said opening from one end thereof and to be screwed out of said opening at the other end thereof, said closure having at its outer side means for establishing a supporting connection between said closure and an actuating device.

13. An ink cartridge for a fountain pen comprising a tubular member closed at one end and having an opening through its other end, said opening being of uniform diameter and threaded throughout its length, and a threaded closure of uniform diameter throughout its length adapted to be screwed into said opening from the outer end thereof and to be screwed out of said opening at the inner end thereof, and means to prevent said closure being withdrawn through the outer end of said opening.

14. An ink cartridge for a fountain pen comprising a tubular member closed at one end and having an opening through its other end, said opening being of uniform diameter and threaded throughout its length, and a threaded closure of uniform diameter throughout its length adapted to be screwed into said opening from the outer end thereof and to be screwed out of said opening at the inner end thereof, and a stop secured to said cartridge and overlying the outer end of said closure.

In testimony whereof, I affix my signature hereto.

WILLIAM J. WOOLDRIDGE.
